DOOR HINGE

Filed Sept. 28, 1929

INVENTOR
Gustav Bommer
BY C. C. Hooper
His ATTORNEY.

UNITED STATES PATENT OFFICE

GUSTAV BOMMER, OF BROOKLYN, NEW YORK, ASSIGNOR TO EMIL BOMMER,
OF BROOKLYN, NEW YORK

DOOR HINGE

Application filed September 28, 1929. Serial No. 395,792.

This invention relates to hinges for doors, the invention being more particularly related to hinges of the kind whereby the closing movement of the door is effected by gravity, and the invention is especially designed for use in connection with doors of the kind commonly employed in connection with toilet rooms and compartments, although its use is not confined to that particular kind of doors.

- 10 More particularly, the purpose and object of the present invention are the provision of certain improvements in the type of gravity hinge which embodies an anti-friction member in the form of a roller in cooperation with a curved track, the improvements relating to a simplified construction which will be economical to manufacture and easy to assemble and which will be strong, durable and highly efficient in use.
- 15 Another object of the invention is the provision of a hinge of the character described, which will embody novel features of adjustment whereby the door can be readily aligned with respect to the frame or casing, and whereby through the adjustment of the parts of the hinge the door will automatically close to the determinate position desired.

Other objects and advantages will appear hereinafter.

- 20 The invention consists in the improved hinge structure and in the form, construction and relative arrangement or arrangements of parts, as will be hereinafter more fully described and subsequently incorporated in the subjoined claims.

For a full understanding of the invention, reference is to be had to the accompanying drawings, forming a material part of this application, and in which—

- 25 Figure 1 represents a fragmentary elevational view, showing the hinge applied to the door;

Fig. 2 represents a section and elevation on a larger scale, taken in the direction indicated by the line 2—2 on Fig. 1;

Fig. 3 represents another section and elevation, taken substantially at right angles to that on which Fig. 2 is taken;

Fig. 4 represents an underneath plan view of the cylindrical body, with the frame bracket and anti-friction means removed, this view being taken on the line 4—4 of Fig. 3; and

Fig. 5 represents a top plan view of the frame bracket and antifriction means supported thereby.

Referring with more particularity to the parts illustrated in the accompanying drawings, the numeral 10 designates a fragment of a door frame while the numeral 11 designates a door supported on the frame for self-closing movement, the door being of the type commonly employed in connection with toilet compartments and rooms. Inasmuch as the door is arranged to close by the force of gravity, it is necessary to provide a mounting which will permit the door to have vertical movement bodily during its swinging movements; and to this end the door is provided at its top with any type of hinge connection adapted to properly maintain the door at its top end for such vertical movement.

In the accompanying drawings, the hinge connection at the top end of the door is represented as comprising a plate 12 which is secured to the top edge 13 of the door and which is provided with an upright pintle 14 having turning and sliding fit in the horizontal part 15 of an elbow bracket 16 suitably secured to the frame 10. This is an ordinary type of hinge connection for the purpose and comprises no part of the present invention, being illustrated herein merely to show how the door may be maintained at its top end for vertical movement.

The preferred form of construction, as illustrated in the accompanying drawings, comprises a horizontal bracket 17 including parallel upstanding side flanges 18 adapted

to embrace the opposite sides of the door as shown. Said bracket 17 may be secured to the door by any suitable means, as by screws 19 and 20 passed through suitable holes in the bracket and threaded into the material of the door. With the bracket 17 is associated a depending cylindrical body indicated generally at 21 and comprising a head or top 22, a central depending sleeve or hub 23 and a depending concentric shell or apron 24 which extends below the lowest portion of the sleeve and is open at the bottom. These parts are arranged so as to provide an annular space 25 between the sleeve and apron. According to a feature of the construction, the lower end of the sleeve 23 is made in the form of a curved track, curving downwardly from the opposite sides of a seat or dwell 26 to a low point 27, the numerals 28, 28 indicating the two sides of the track curving downwardly from said seat 26 to said low point 27.

29 denotes an upright stud or pin on which the sleeve 23 is fitted to have turning and sliding movement, and 30 denotes an anti-friction device in the form of a roller on which the curved track moves during the swinging movements of the door. The stud 29 is illustrated as having a shoulder 31, a reduced portion 32 below the shoulder and a further reduced portion 33 provided with screw threads. For operatively supporting the door for swinging movement, I preferably provide a bracket 34 which is secured to the adjacent edge or face 35 of the frame 10 by any suitable means, for instance as by screws 36. Said bracket 34 is formed with a horizontal part or shelf 37 provided therein with a vertical opening or bore 38 in which the portion 32 of the stud is fitted to have turning movement. The roller 30 is mounted for rotation upon a spindle 39 having its inner end secured in the stud 29 and its outer portion secured in a supporting bracket 40 of the elbow type. As shown in Fig. 3, the horizontal part 41 of the bracket rests upon the shelf 37 and surrounds the reduced portion 32 immediately underneath the shoulder 31. Thus interposed between the shoulder of the stud and the shelf, the horizontal part 41 of the bracket 40 serves as means for supporting the stud upon the shelf and as well for supporting thereon the cylindrical body 21 and door 11, it being of course manifest that the weight of the door at all times is imposed upon the roller 30 through the engagement therewith of the track at the lower end of the sleeve. The horizontal part 41 is made rigid with the stud in any suitable manner, as by welding, soldering or otherwise, so that the stud, bracket 40, and spindle 39 constitute in effect a one-piece structure, the position of which is adapted to be adjusted by turning the stud in the shelf part 37. By means of a securing nut 42 applied to the threaded portion 33 of the stud, it is possible

readily to secure the stud, bracket 40 and roller 30 in that position of adjustment desired. Manifestly the stud and parts associated therewith are secured in the relative position desired by turning the securing nut 42 tightly against the underside of the horizontal shelf 37.

In use, the parts are so adjusted that the seat or dwell 26 will receive the roller 30 when the door is in that position which it is to occupy when closed. By moving the door from closed position, the track moves upon the roller, which is turned thereby, and forces the door to rise vertically, the pintle 14 sliding upwardly in the bracket 15, so that when the door is released the closing movement thereof will be automatically effected by force of gravity, the track again moving over the roller until it reaches that position in which the roller will engage the seat or dwell 26.

The framing and door posts of toilet compartments and rooms are frequently out of alignment so that it is difficult to hang the door for proper swinging movement and to close it to the desired position where it will appear to be aligned to the best advantage. By means of the hinge structure herein disclosed it is an easy and simple matter not only to hang the door but also to so hang it to the frame that it will, when closed, have the desired position of alignment. Moreover, where the frame or other parts go out of alignment or require readjustment, it is an easy matter to readjust the door, it being only necessary to loosen the securing nut 42 and adjust the stud so that the seat or dwell 26 will engage the roller at the position in which the door is properly adjusted with respect to the frame or with respect to an adjacent door. After such adjustment has been effected, the securing nut 42 is thereupon tightened to secure the parts in their adjusted position.

The device of the present invention is exceedingly simple, composed of few parts, inexpensive to manufacture and easy to assemble. Moreover, the construction provides for quick mounting of the door in the adjusted position desired and by ordinary labor.

From the foregoing description, taken in connection with the accompanying drawings, it will be manifest that I have disclosed an extremely simple and thoroughly satisfactory form of construction which embodies the features of advantage enumerated in the statement of invention, and while I have, in the present instance, shown and described a preferred embodiment thereof as reduced to practice, it is to be understood that the construction is susceptible of modification in various particulars without departing from the spirit or scope of my invention or sacrificing any of its advantages.

I claim:

1. In a gravity type hinge, a part for con-

nection to the door frame including a horizontally projecting shelf, a part for connection with the lower horizontal edge of the door, provided with a hollow depending sleeve whose lower free edge includes an elevated seat and a track curving downwardly from the seat, a vertical stud and an elbow joined together, the latter including a vertical arm forming a space with the stud, a roller on which the lower free edge of the sleeve can turn for the support of the door and for receiving the elevated seat to determine the position of the door, when closed, with respect to the door frame, said roller being situated in said space and turning on an axis between the stud and arm, and means for supporting the stud upon the shelf for circular adjustment to locate the roller at the determinate position in which the seat must be retained for accurately aligning the door, when closed, with the door frame.

2. In a gravity type hinge, the combination of a first part adapted to be connected to the door frame and having a horizontally projecting shelf, a second part adapted to be connected with the lower horizontal edge of the door, a hollow sleeve depending from the second part and having a lower free edge formed with an elevated seat and a track curving downwardly from the seat, an adjustable means for mounting the sleeve on the shelf, including a vertical stud having its lower portion fitted for circular adjustment on the shelf and its upper portion turnably fitted in the sleeve, a plate joined to the stud to turn therewith and supporting the stud upon the shelf, an arm rising from the plate and forming a space with the side of the stud, and a roller on which the lower free edge of the sleeve can turn, adapted for receiving the elevated seat to determine the position of the door, when closed, said roller being located in said space and mounted on an axis extending between the stud and said arm.

3. In a gravity type hinge, a first part adapted to be connected to the door frame and provided with a horizontally projecting shelf, a second part adapted to be connected with the lower horizontal edge of the door and provided with a hollow depending sleeve having a lower free edge formed with an elevated seat and a track curving downwardly from the seat, a cylindrical stud on which the sleeve has turning fit projecting below the track and elevated seat, a roller engaging under the track and adapted to receive the elevated seat to determine the position of the door, when closed, with respect to the door frame, means associated with the stud operatively supporting the roller so that the stud and roller can together be adjusted about the axis of the stud to establish with respect to the door frame the position in which the seat will engage the roller whereby accurately to

align the door, when closed, with the door frame, means for supporting the stud upon the shelf for axial adjustment thereon, including a horizontal part fixed to the stud to turn therewith and resting on the shelf to turn thereon, an axial portion on the stud fitting a bearing in the shelf, and means for securing the axial portion to the shelf.

In testimony that I claim the foregoing as my invention, I have signed my name hereto.

GUSTAV BOMMER.
